UNITED STATES PATENT OFFICE.

JACOB STEIGH AND EARL F. CHOATE, OF TAFT, CALIFORNIA.

EARTH-BORING SAMPLER.

Application filed August 11, 1923. Serial No. 656,911.

To all whom it may concern:

Be it known that we, JACOB STEIGH and EARL F. CHOATE, citizens of the United States, residing at Taft, in the county of Kern and State of California, have invented certain new and useful Improvements in Earth-Boring Samplers; and we do hereby declare the following to be a full, clear, and exact description of the invention, such as will enable others skilled in the art to which it appertains to make and use the same.

The object of the present invention is the provision of means for obtaining a sample or specimen of the strata through which an opening is bored in the formation of an artesian or oil well.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a sectional view of a device embodying the invention,

Figure 2 is a view of the cutting end,

Figure 3 is a horizontal section on the line 3-3 of Figure 1, and

Figure 4 is a detail view of the upper portion of the sampling tube.

Corresponding and like parts are referred to in the following description and designated in the several views of the drawings by like reference characters.

The numeral 1 designates the sampling tube which may be of any capacity and which is open at its lower end and closed at its upper end which is reduced, as indicated at 2, and provided with a vent opening 3 which is controlled by means of a valve 4. A casing 5 encloses the sampling tube 1 and is coupled at its upper end to an operating rod or bar 6 which is adapted to be rotated in any preferred manner. A

sleeve 7 encircles the reduced portion 2 of the sampling tube and ball bearings 8 are interposed between the sleeve 7 and the reduced end portion 2, said sleeve being se-

cured within the upper portion of the casing 5. The operating rod or bar 6 is formed with an opening occupied by a pipe 9 through which water or other medium is supplied to facilitate the operation of the device. By-pass pipes 10 connect the lower end of the pipe 9 with the upper portion of the casing 5 but below sleeve 7, whereby to supply the fluid medium thereto. An annular cutter 11 is fitted to the lower end of the casing 5 and is rotatable therewith. Set screws 12 secure the sleeve 7 in casing 5 and permit the removal thereof and removal of the sampling tube 1.

In the operation of the device, the same is lowered into the earth boring and when reaching the bottom of the opening, the rod or bar 6 is rotated and the cutter 11 separates a portion of the strata in the form of a cane which enters the tube 1, the air displaced escaping through the vent opening 3. The contact of the sampling tube 1 with the earth or strata prevents rotation thereof and the annular cutter 11 separates a portion which snugly fits within the tube 1 and enters the same as the device is lowered. After the device has been lowered a distance corresponding to the length of the sampling tube 1, the device is withdrawn from the opening and carries with it that portion of the strata contained within the tube 1 which constitutes a sample or specimen of the strata through which the boring has been made.

What is claimed is:

1. A device of the character specified consisting of a casing, an operating means for the casing, a sampling tube located within the casing, means within the casing supporting said sampling tube, said casing having cutting means at its lower end, and means of fluid supply through said operating means having a pipe extending exteriorly of the casing and having communication with the interior of the casing below said supporting means.

2. A device of the character specified consisting of a casing having substantially the same interior diameter throughout, an operating means connected to the casing, a sampling tube located within the casing, said sampling tube having a reduced portion at its upper end, means within the casing surrounding said reduced portion and

supporting said sampling tube, said reduced portion at its upper end having a vent opening therethrough, said casing having cutting means at its lower end, and means of fluid supply through said operating means having a passage extending exteriorly of the casing and being in communi-

cation with the interior of the casing below said supporting means.

In testimony whereof we affix our signatures.

JACOB STEIGH.
EARL F. CHOATE.
